LOCK, LATCH, AND THE LIKE

Erastus C. Deal, Wilkes-Barre, Pa., assignor to
 Deal Slide-Lock Devices, Inc., Bronx, N. Y., a
 corporation of New York

Application August 7, 1942, Serial No. 454,049

13 Claims. (Cl. 292—167)

The present invention relates to locks and locking devices and more particularly to means for increasing the security and adaptability of latches, locking devices and the like.

The purpose of a lock is generally two-fold; first, to hold a door or other element closed and to permit it to be opened by turning a knob or a similar device; and secondly, to lock the door so that it cannot be opened without a key. The present invention is adapted for both of these purposes and for various other purposes in preventing slippage and creepage of mechanical elements subjected to pressure, vibration and the like.

The form of lock commonly used heretofore has a retractable member with a cam surface on one side which engages the door casement when the door is closed to retract the member and to permit it to snap into a recess provided in the casement for holding the door closed. There is usually a space between the door and the casement through which one can insert the blade of a knife and by careful manipulation retract the member to open the locked door. Frequently the retractable member and the recess into which the retractable member projects becomes worn until the engaging surfaces become rounded. This produces a camming action tending to force the locking member into its retracted position permitting the door to open. If the parts are subject to vibrations by reason of their environment, the camming action is accentuated. Such worn parts cause car and other vehicle doors to open, thereby subjecting passengers to serious accidents. Frequently also, the fit between the door and the casement is not accurate and the door is permitted to rattle because the relative position of the retractable member and the recess is not such as to hold the door tightly closed. In other cases, in connection with refrigerators, resilient seals are provided between the door and the casement. These seals become worn and require the door to be closed more tightly to obtain good results. In such cases, the position of the lock or the recess has to be changed from time to time in order to obtain the desired results. The present invention provides a simple means of minimizing or overcoming the above objections.

An object of the present invention is to provide an improved locking device having wide applications.

Another object of the invention is to provide a more secure locking device.

Another object of the invention is to provide an effective locking member which cannot be retracted by pressure applied to the exposed or effective part thereof.

Another object of the invention is to provide an improved means for preventing pressure ap-

plied to the exposed part thereof from retracting the locking member.

Another object of the invention is to provide a device which will hold securely on a worn locking recess or on an angularly disposed surface.

Another object of the invention is to provide an effective locking means which will prevent accidental opening of car doors and the danger resulting therefrom.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein

Fig. 1 is a top plan view of a preferred embodiment of the lock applied to a door;

Fig. 2 is a side elevational view of the lock illustrated in Fig. 1 viewed from the inside of the door;

Fig. 3 is a sectional view of the lock taken along the line 3—3 of Fig. 2;

Fig. 4 is a horizontal sectional view taken along the line 4—4 of Fig. 3;

Fig. 5 is a side-elevational view from the inside of the door of a slightly different form of lock;

Fig. 6 is an end view of the lock illustrated in Fig. 5;

Fig. 7 is a view from the inside of the door of another form of the lock embodying the present invention;

Fig. 8 is a vertical sectional view along the line 8—8 of Fig. 7;

Fig. 9 is an enlarged fragmentary view illustrating the operation of the lock in obtaining different degrees of tightness and in preventing accidental opening of doors having worn recesses;

Fig. 10 is a detailed view of a modified form of retractable member.

Referring again to the drawings illustrating a preferred embodiment of the invention and more particularly to Figs. 1 to 4, thereof, there is shown a movable member 1, which may, for example, be a door and a casement or fixed member 2 having a recess 4 for the reception of a retractable member 5 of a lock 6.

A pair of wedge members 7 and 8 are mounted back of the retractable member 5 for purposes which will be described hereinafter. The retractable member 5 is operatively connected to the door handle 9 through the intermediation of a bracket 10, which may be welded to the retractable member 5, link 11 connected at one end to bracket 10 by a stud 12 and at its other end to a link 14 by a stud 15, link

14, and rod 16 operatively connected to the opposite end of the link 14 and extending through the door to connect with the handle 9. Operation of the handle 9 through the link mechanism described, retracts the member 5 for opening the door. The retractable member 5 is held in its outermost position as shown in Figs. 1 and 2 by means of a spring 18 extending about a stud 19 on the casing and a stud 20 on the end of the member 5. The distance that the retractable member 5 may move under the influence of the spring 18 is determined by a projection 21 which serves as a stop for the member 22 on link 14.

A suitable channel or casing 24 may be secured to the door by means of brackets welded or otherwise secured thereto and screws 26. The shape of the channel member 24 may be substantially rectangular in section with inwardly bent flanges at the sides thereof to expose the inner side of the retractable member 5 for the attachment of the bracket 10 and to facilitate the connection of the wedge members thereto. The retractable member 5 has a cam surface 28 which is adapted to engage the edge of the casement when the door is closed so that the member may retract and snap into the recess 4. Without the wedge members 7 and 8, there would be little difficulty in inserting a knife in the clearance space at 29 and forcing the retractable member back in steps until the door could be opened. Likewise, if the edge of the recess should be worn as indicated in dot-dash lines at 30, or if the end of the retractable member should be worn, there would be a tendency for the member 5 to be forced into its retracted position. If the door were on a car where it would be subject to constant jars and vibrations, this tendency would be increased and, in many cases, the door would open, causing damage to the car and likelihood of injury to occupants who might fall out, if leaning against it.

The wedge members 7 and 8 and the parts associated therewith are for the purpose of providing means to prevent movement of the member 5 into retracted position by pressure on the exposed end of the wedge member 7. On the other hand, the wedge member 7 and the member 5 may be readily retracted by pressure on the retractable member 5 which occurs whenever the door is closed and when the handle 9 is turned.

The wedge members and their associated parts comprise a wedge 7 having a wedge surface 7' and an exposed end 7''. The wedge member 8 has a wedge surface 8' abutting the wedge surface 7'. A flexible member 32, here shown as a strip without any intention of being restricted to the form shown, extends between the wedge surfaces 7' and 8' and has its ends fixed in position by being bent over and soldered to the diagonally opposite ends of the casing at 32' and 32''. These ends may be secured in position either to the casing or to some other part of the door in any other suitable manner. As the wedge members are moved back and forth in the channel casing, the wedge surfaces move along the flexible strip 32.

The wedge members are operatively connected to each other by means of a spring 34 which has its ends bent to fit in recesses 35. Any other suitable means, such as studs, may be used for anchoring the ends of the spring to the wedge members. The spring tends to pull the two members toward each other and is sufficiently resilient to permit them to move apart slightly and thereby release the flexible strip which is intermediate the wedge surfaces so that the wedges may move along the channel. The wedge members are also

connected respectively to the retractable member 5 by means of screws 37 and 38 passing through the retractable member and extending into slots 37' and 38' in the wedge members. Each of the slots 37' and 38' is elongated slightly and the slots are so located that when the retractable member is moved toward its retracted position, the screw 38 engages the end of the slot 38' prior to the engagement of the screw 37 with the end of the slot 37'. This permits the wedge member 8 to be moved away slightly from the flexible member 32 so that it is released to permit it to slide between the wedge surfaces. The screw 37 subsequently engages the end of the slot 37' to cause the wedge member 7 to follow up the wedge member 8 in the event that the spring permits the wedge members to move apart sufficiently for the screw to engage the end of the slot 37'. Hence both wedge members move with the member 5 into retracted position. When the retractable member 5 is moved in the opposite direction under the influence of the spring 18, the screw 37 engages the end of the slot 37' which moves wedge members apart to permit the flexible strip 32 to slide between the wedge surfaces. Thus the wedge member 7 is moved to the left and the spring 34 tends to draw the wedge member 8 behind it. If the spring permits the wedge members to draw apart sufficiently, the screw 38 will engage the end of the slot 38' and cause the wedge member 8 to follow. The elongated slots 37' and 38' cooperate with the screws 37 and 38 to form a lost-motion connection, whereby the wedge members are separated slightly by the retractable member 5 when moved in either direction. This separation unclamps the flexible member 32 intermediate the wedge surfaces 7' and 8' and permits the members to move freely with the retractable member 5.

40 It is to be noted that the extreme end of the member 5 extends beyond the end of the member 7. This is desirable because of the lost-motion connection between the two. The retractable member 5 has to move a short distance before it becomes effective in retracting the wedge members 7; hence the difference in length of the exposed portions of the wedge member 7 and the retractable member 5.

45 The spring 34 serves resiliently to urge the two wedge members together and to cause them to follow up each other. The spring is not sufficiently strong to prevent the members from being separated under the action of the retractable member 5. In fact, the spring may be eliminated entirely without rendering the device inoperative. However, the operation of the device is improved by utilizing the spring in addition to the loose link connection with the retractable member 5. The free movement of the wedge members in either direction under the influence of the retractable member 5 will be clear from the above description.

50 If, however, one inserts a knife blade in the space 29 shown in Fig. 1 and attempts by engaging the exposed portion 7'' of the wedge member 7 to retract the wedge member 7, the pressure applied will force the wedge surface 7' against the wedge surface 8' with the flexible member 32 clamped therebetween. The greater the pressure 55 tending to retract the wedge member 7, the greater will be the clamping action due to the friction between the wedge members 7 and 8 and the flexible member 32 and also to the friction between the wedge members and the sides of the casing. Hence, the wedge member is locked

against retraction except through the intermediation of the retractable member 5. Likewise, if the front of the recess becomes worn and somewhat rounded, as shown by the dot-dash line at 30, the tendency of the cam action of the rounded part to force the wedge members 7 backward will have the same effect. That is, it will tend to clamp the flexible member 32 between the wedge surfaces and lock the wedge members securely in position. In some cases, where the front of the recess is worn, the retractable member and the exposed portion 7' of the wedge member 7 may not go fully into the recess, but may stop along the incline or rounded portion 30. In that case, the door will nevertheless be held securely in position since the cam action will be on the exposed portion 7'' of the wedge member 7 and not on the retractable member 5. If the door should rattle, the spring member 18 will force the wedge member 7 and the retractable member 5 completely into the recess. Thus the security of the lock, both in holding the door 2 under the unusual conditions and in preventing unauthorized persons from opening the door, are improved. The recesses 5' in the sides of the retractable member are for the purpose of accommodating the front ends of the flange 21.

As illustrated in Figs. 2 and 3, a suitable cover 40 may be mounted on pins or posts 41 to cover the links 11 and 14 and the mechanism associated with the door handle on the inside of the door.

Referring more particularly to Figs. 5 and 6, a similar construction is shown operating on a similar principle. The parts for convenience have been correspondingly numbered. The difference between the construction there shown and the one described above in connection with Figs. 1 to 4 is the connection of the handle 9 to the retractable member 5 by means of links 14' and 13. These are located on the outside of the cover 40 whereas the link mechanism in Figs. 1 to 4 is enclosed within the cover. Springs 44 and 45 supplement the action of the spring 18 in returning the retractable member 5 and may be omitted without impairing the utility of the device, or if desired, springs 44 and 45, or either of them, may be used as a substitute for spring 18.

The mechanism illustrated in Fig. 7 likewise differs from the preferred embodiment in the connection of the handle 9 with the retractable member 5. In this embodiment, the link 14'' corresponding to the link 14 in the preferred embodiment, fits through slots 46 in the side of the casing into a recess 47 in the retractable member 5, thereby eliminating the necessity for additional links such as the link 11 and bracket 10 in the preferred embodiment.

The lock is illustrated in Fig. 9 and applied to the door of a refrigerator, where a substantially hermetic seal is required. For this purpose, a rubber gasket 48 is placed intermediate the door 1' and the casement 2'. The recess 4' has the lock engaging side 30' thereof at an angle to the plane of the door casement. It has been found that with age, the rubber cushion 48 used for sealing the door becomes hard and either wears or shrinks; hence, with ordinary locks or latches, it is not possible to obtain a good seal without adjustment of the relative positions of the latch member and the recess from time to time. With the construction illustrated in Fig. 9, a very secure seal is assured at all times. As the gasket 48 wears or contracts, the door is closed tighter and the retractable member 5 and wedge 7 enter fur-

ther into the slot and engage the surface 30' at a different position. Hence, the inclined surface 30' automatically takes care of any wear or variation in the thickness of the gasket 48. As pointed out above with respect to the preferred embodiment, the inclined surface 30' may apply a force on the exposed portion of the wedge 7 which tends to retract it but such force serves to lock it securely in position through the intermediation of the wedge surfaces 7' and 8', the flexible member 32 and the sides of the casing as described in connection with the preferred embodiment.

In the modification illustrated in Fig. 10, the wedge member 7 is set into a channel 49 in the upper surface of the retractable member 5. This construction decreases the over all extension of the upper side of the wedge member 7 above the side of the member 5 on which it is mounted. Where this construction is used, the sides of the retractable member should be recessed at 50 to avoid interference with the flexible member 32.

The operation of the device will be clear from the description given in connection with the preferred embodiment illustrated in Figs. 1 to 4 and further elaboration at this point would be superfluous.

It will be seen that the present invention provides an improved lock for various doors, including car doors, which has features of increased security, both from the standpoint of preventing accidental opening and from the standpoint of preventing unauthorized persons from opening the door. While a key mechanism for operating the lock is not shown, it will be understood that any suitable arrangement can be utilized for this purpose. With or without the key mechanism, the lock has distinct advantages. The parts required for the additional security are of a simple nature and may be added without substantial increase in cost. The parts are rugged in construction and hence there is little likelihood of any breakage, but if such a contingency occurs, the parts may be readily removed and replaced.

As various changes may be made in the form, construction and arrangement of the parts herein without departing from the scope and spirit of the invention and without sacrificing any of its advantages, it is to be understood that all matter herein is to be interpreted as illustrative and not in a limiting sense.

Having thus described my invention, I claim:

1. In a door lock of the class described, the combination of a member adapted to move in a predetermined direction to secure and release a door, a pair of wedge members having opposed wedge surfaces, means responsive to the movement of said first member for moving said wedge members and means, including a flexible member extending between the wedge surfaces of said wedge members and having its ends fixed in position, for locking said wedge members against movement except in response to the movement of said first member.

2. In a lock, the combination of a member adapted to move when engaged by an object such as a door casement, and adapted to return to its original position when disengaged, a second member operatively connected to said first member and means, including a flexible member in frictional engagement with said second member, for locking said second member against movement in one direction except in response to the movement of said first member.

3. In a lock, the combination of a member

having a cam surface on a side thereof adapted to move said member when engaged by an object such as a door casement, a wedge member extending along the side of the first member opposite to the cam surface, means including a pin and slot connection for operatively connecting said members and means including a second wedge member for locking said first wedge member against movement in one direction except in response to the movement of said first member.

4. In a door locking device, the combination of a retractable member having a cam surface adapted to engage a door casement and to move said member into retracted position, a second member movable with said retractable member and having an exposed portion adapted to engage the door casement to hold the door closed and means including a flexible strip in frictional engagement with said second member for preventing the retracting of said second member by pressure applied to said exposed portion.

5. In a door locking device, the combination of a retractable member having a cam surface adapted to engage a door casement and to move said member into retracted position, a pair of wedge members movable with said retractable member, said wedge members having opposed wedge surfaces, one of said wedge members having an exposed portion adapted to engage the door casement to hold the door closed and means for preventing the retraction of said wedge member by pressure applied to said exposed portion.

6. In a door locking device, the combination of a retractable member having a cam surface adapted to engage a door casement and to move said member into retracted position, a pair of wedge members operatively connected to and movable with said retractable member, said wedge members having opposed wedge surfaces, one of said wedge members having an exposed portion adapted to engage the door casement to hold the door closed and means, including a flexible member extending between the wedge surfaces of said wedge members with its ends fixed in position, for preventing the retraction of said one wedge member by pressure applied to said exposed portion.

7. In a door locking device of the class described, the combination of a member having a cam surface adapted to engage a door casement for movement in a predetermined direction, a pair of wedge members having opposed wedge surfaces, means connecting said first member and each of said wedge members and permitting only limited relative movement therebetween whereby substantial movement of said first member in one direction will be effective upon one of said wedge members to move the pair of wedge members and substantial movement in the opposite direction will be effective upon the other of said wedge members to move the pair of wedge members in the opposite direction and means for locking said wedge members against movement except in response to the movement of said first member.

8. In a device of the class described, the combination of a latch member having a cam surface adapted to be engaged for movement in a predetermined direction, a pair of wedge members having opposed wedge surfaces, means loosely connecting said first member to said wedge members effective to move each wedge member in a direction away from the other wedge member, and a flexible member extending between said

wedge surfaces having its ends fixed in position to lock one of said wedge members against movement in a direction away from the cam surface except in response to movement of said first member.

5. In a device of the class described, the combination of a retractable member having a cam surface for engaging a door casement, means for retracting said retractable member, a pair of wedge members operatively connected to said retractable member for movement therewith, said wedge members having opposed wedge surfaces and means for locking said wedge members against retraction except in response to the movement of said first member.

10. In a door latch or the like, the combination of a movable member having a cam surface adapted to engage a strike plate and to be moved thereby into its retracted position to permit the closing of a door, a pair of wedge members having opposed wedge surfaces, a casing extending along the sides of said wedge members and means permitting relative movement between the wedge members and the movable member for connecting said wedge members to said movable member, said movable member through said connecting means being adapted to move one of said wedge members having opposed wedge surfaces away from the other when said movable member is moved in either direction.

15. In a door latch or the like, the combination of a movable member having a cam surface adapted to engage a strike plate and to be moved thereby into its retracted position, a pair of wedge members having opposed wedge surfaces, means extending along the sides of said wedge members to hold them substantially in aligned position, and connections including pins in slots for connecting each of said wedge members to said movable member and for permitting said opposed wedge surfaces thereon to move into interlocking relation.

20. In a door latch or the like, the combination of a movable member having a cam surface adapted to engage a strike plate and to be moved thereby into its retracted position, a pair of wedge members having opposed wedge surfaces, means extending along the sides of said wedge members to hold them substantially in aligned position, connections including pins in slots for connecting each of said wedge members to said movable member and a metal strip extending between and separating said wedge surfaces, said metal strip having the ends thereof stationary with respect to said wedge members, the movement of said movable member in either direction being effective through the connections with the wedge members to further separate the wedge surfaces and to permit said strip to slide therebetween.

25. In a door latch or the like, the combination of a movable member having a cam surface adapted to engage a strike plate and to be moved thereby into its retracted position, a pair of wedge members carried by said movable member and having opposed wedge surfaces, the end of one of said wedge members being substantially flush with the end of said movable member adjacent the cam surface thereof, means for connecting said wedge members to said movable member including pins fitting in slots to permit limited relative movement between the wedge members and said movable member and a guide-way for retaining said wedge members movably in position.
